BUCKLE

Leon Bernstein, Brooklyn, N. Y.

Application May 31, 1933, Serial No. 673,635

6 Claims. (Cl. 24—191)

This invention relates to improvements in buckles and similar articles adapted for fastening or connecting separable parts together. While the buckle is designed primarily for use with belts for articles of wearing apparel, such as ladies' dresses, coats and the like, the construction may, of course, be utilized for such articles adapted for use for other purposes.

The principal object of this invention is the provision of such a device which is simple in construction, composed of few parts, simple and cheap to manufacture and assemble, strong in construction, secure as far as fastening or connecting is concerned, and which is ornamental and attractive in appearance.

Another object of this invention is the provision of such a device which is composed essentially of three major parts which may be readily and securely assembled together in operative relationship so as to form a complete article, which may be formed so that in use it is ornamental due to different materials used in covering or in connection with the same.

To the accomplishment of the foregoing and such other objects as may hereinafter appear, this invention consists in the construction, combination and arrangement of parts hereinafter described and then sought to be defined in the appended claims, reference being had to the accompanying drawing forming a part hereof and which shows, merely for the purpose of illustrative disclosure, several embodiments of my invention, it being expressly understood, however, that various changes may be made in practice within the scope of the claims without digressing from my inventive idea.

In the drawing—

Figure 1 is a front elevation of a buckle constructed in accordance with my invention, shown attached to a belt for a garment and showing the use of contrasting colors or materials for ornamental purposes.

Figure 2 is a transverse section taken substantially through the middle of Figure 1 on a diameter of the buckle parallel to the length of the belt.

Figure 3 is a front elevation of a buckle of similar construction to that shown in Figure 1, embodying a slight modification.

Figure 4 is a transverse section taken substantially through the middle of Figure 3 on a diameter of the buckle parallel to the length of the belt.

Figure 5 is a front elevation of another buckle

constructed in accordance with my invention, slightly modified from that shown in Figure 1.

Figure 6 is a transverse section taken substantially through the middle of Figure 5 on a diameter of the buckle parallel to the length of the belt.

Referring first to Figures 1 and 2 of the drawing, the numeral 1 designates the top or front shell or part of the buckle, the numeral 2 the bottom or rear ring or annulus and the numeral 3 the intermediate clip or clamp holding disc or plate. Described differently, the front part of the buckle consists of a shell in the form of a shallow receptacle 1 with which is combined so as to be contained therein a rear part made up of annulus and disk portions designated respectively 2 and 3.

The top or front shell is disc-like in shape and appearance and while shown as circular may be made in various shapes and confirmations. It has a rearwardly turned peripheral edge or marginal portion 4 which is turned in beyond the perpendicular to form a sort of inturned cup to receive the bottom or rear ring or annulus, the inturned edge forming an inclined inner surface to engage over the outer surface of the edge of the ring or the annulus, as hereinafter described. The body portion of this top shell may be formed with an opening 5 therethrough which may be of any shape or configuration. In Figures 1 and 2 the opening is shown of diamond shape. In Figure 5 this top shell is shown as imperforate or without an opening.

The bottom or rear ring or annulus is formed of such a size as to fit closely within the inturned flange 4 of the top shell 1 and to be clamped therewithin. Cross sectionally, it is in the form of an inverted channel groove or trough preferably having its outer edge 6 rather steeply inclined and the body portion 7 and the other or inner edge 8 of more gradual inclination as clearly shown in the cross sectional views. The outer edge 6 of the bottom ring or annulus is adapted to fit against the inturned flange 4 of the top shell which engages said edge portion 6 and is clamped thereto so as to hold the parts securely in assembled relation. Of course, this annulus 2 corresponds in shape to the top shell 1.

The intermediate disc or plate 3 is interposed between the top or front shell 1 and the bottom or rear ring or annulus 2 and is held in position therebetween by the clamping of the ring or annulus and shell together. This intermediate disc or plate 3, of course, corresponds in shape to the shell as it fits within the flanged portion 110

- thereof. It may be imperforate as shown in Figures 1 and 2, or it may be provided with an intermediate opening 9 (see Figure 4) to correspond with the opening 5 in the top shell 1.
- 5 This intermediate disk or plate of the back part of the buckle is adapted to support the clamp or clip 11 within the shallow receptacle constituting the front part of the buckle and is provided with the upstanding apertured ears 10, 10 in which the clamp or clip member 11 is journaled by means of the lateral studs 12. This member 11 is in the form of a plate formed of two portions, the shorter portion 13 constituting the clamping member or part and adapted to 15 clamp the belt material against the face of the intermediate disc or plate (see the cross sectional views). The longer portion or part 14 of the member 11 extends at substantially right angles to the clamping part 13 and functions as 20 a handle or operating portion to move the flange or gripping portion 13 to and from operative position. It is also provided with the slot or aperture 15 adapted to receive one end of the belt, it being understood that the other end of the 25 belt is passed between the clamping portion 13 and the intermediate disc or plate 3 and securely held when the clamp or clip member is in the position shown in Figures 2, 4 and 6.
- I have illustrated these various parts as being 30 formed of metal, but it is to be understood, of course, that they may be formed of other suitable materials. They may be very readily stamped out and then forced into an assembled relationship with a minimum amount of time and skill on the part of the operator.
- 35 The parts may be used in an uncovered form as shown in Figures 5 and 6, or they may be covered by suitable material when designed to be used with certain classes of apparel. For instance, in Figure 1, the top or front shell 1 is covered by any desired fabric 16 as is the bottom or rear ring or annulus 2. If it is desired to have some contrast for ornamental purposes, a different material 17 may be interposed between the intermediate disc or plate 3 and the 40 inside of the top or front shell 1. Such material would thus be exposed through the opening 5 in the top shell as shown in Figures 1 and 2. Or, if it is desired to have the belt itself show through the opening 5 that can be accomplished by the arrangement shown in Figures 3 and 4 where both the top or front shell 1 and the intermediate disc or plate 3 have openings which are arranged in alignment with each other.
- 45 It is therefore seen that I have provided a device of the character described whose parts may be readily manufactured and assembled in secure relation to each other. Furthermore, I have provided means whereby striking and ornamental effects may be obtained, and the article used either in the form of a covered buckle or in the form of an uncovered buckle.
- 50 What I claim is:
1. A device of the character described, including in combination, a front shell having an in-turned marginal flange, an intermediate clamp holding member and a rear annulus fitting with in the marginal flange of the front shell and holding the intermediate member in position therewith; said intermediate member being provided with a pair of spaced apertured ears, a clamping member journaled in said ears to rotate, said clamping member comprising two parts extending 55
- at an angle to each other, one part being the clamping member proper and adapted to engage the material between the clamping member and the intermediate member and the other part forming the operating portion of the clamp. 80
2. A belt-buckle, including in combination, a front shell having an inturned marginal flange to form a shallow receptacle, an intermediate disc in the bottom of said receptacle and carrying a belt clamp, a rear annulus fitting in said receptacle with one marginal flange in close clamping engagement with the edge of the receptacle, said annulus engaging and holding the disc in the bottom of the receptacle, said front shell and said intermediate disc being formed with aligned openings therethrough for exposure of the material of the belt. 85
3. A covered buckle comprising a front shell having its marginal edge turned in to form a shallow receptacle and being formed with an ornamental opening through the body thereof, an intermediate disc carrying a clamp, said clamp having means to receive one end of the belt and the other end of the belt being adapted to be passed between the face of the intermediate disc and the clamp; and a rear annulus channel shaped in cross section and engaging the rear face of said intermediate disc, one edge closely fitting within the inturned marginal edge of the front shell whereby the parts are held securely together. 90
4. A covered buckle comprising a front shell having its marginal edge turned in to form a shallow receptacle and being formed with an ornamental opening through the body thereof, an intermediate disc carrying a clamp, said clamp having means to receive one end of the belt and the other end of the belt being adapted to be passed between the face of the intermediate disc and the clamp; and a rear annulus channel shaped in cross section and engaging the rear face of said intermediate disc, one edge closely fitting within the inturned marginal edge of the front shell whereby the parts are held securely together, the exposed parts of said front shell being covered by a suitable material and another material being interposed between said intermediate disc and the inside of said front shell so as to be exposed through the opening in said front shell. 95
5. A buckle comprising a front shell having its marginal edge turned in to form a shallow receptacle, a rear part comprising a disc like member and an annular member channel shaped in cross section and closely fitting within the inturned marginal edge of the front shell and securely held thereby and a clamp member for a belt pivotally connected to said rear part and positioned within the receptacle. 100
6. A buckle comprising a front shell having its marginal edge turned in to form a shallow receptacle, said shell being formed with an opening through the body thereof, a rear part comprising in combination a disc like member and an annular member channel shaped in cross section with one edge closely fitting within the inturned marginal edge of the front shell and securely held thereby, said disc like member being provided with an opening in line with the first named opening, and a clamp member for a belt pivotally mounted within said rear part. 105
